UNITED STATES PATENT OFFICE.

WILLIAM PARKS ALTER, OF DENNISON, OHIO.

LOCOMOTIVE AIR-BRAKE.

SPECIFICATION forming part of Letters Patent No. 612,149, dated October 11, 1898.

Application filed December 6, 1897. Serial No. 660,906. (No model.)

To all whom it may concern:

Be it known that I, WILLIAM PARKS ALTER, a citizen of the United States, residing at Dennison, in the county of Tuscarawas and State of Ohio, have invented certain new and useful Improvements in Locomotive Air-Brakes; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to locomotive air-brake devices and piping systems, and has for its object the production of an improved engineer's brake-valve and additional connections between the essential elements of an air-brake system, borne upon a locomotive, by means of which the engine-brakes may be manipulated independently of those upon succeeding cars to which the train-pipe is operatively coupled.

25 My invention consists in providing the rotary valve of the brake-valve with certain cavities and its seat with a port leading through the valve-casing and connected by pipes with the exhaust-port of the triple valve, enabling 30 pressure to be applied to the engine brake-cylinder by way of the avenues of the triple valve ordinarily employed to open that cylinder to the atmosphere. To the customary indicated operating positions of the engineer's 35 brake-valve lever I add a "new-position" or "engine - service" demarcation, and upon moving the lever into the new position air from the main reservoir is admitted to the engine brake-cylinder only, no demand being 40 made upon the auxiliary reservoir, as in the regular "service application" of the train-brakes. Release of engine-brakes set as described is effected by turning the lever into the proper "position while running." A suitable 45 pressure-reducing valve mechanism is introduced between triple valve and brake-cylinder.

Each constituent element of my invention is described in detail and its individual office, 50 together with the mode of operation of the whole, hereinafter fully explained.

Like numerals are employed to designate

the same parts throughout the accompanying drawings, whereof—

Figure 1 represents a side view of all the 55 devices save the engineer's brake-valve, a top view of a cross-section of which is shown. Fig. 2 is a plan of the rotary-valve face. As any clear explanation of my invention necessitates that all the parts and connections concerned be shown in one view, the first figure is introduced; but owing to space limitations and to the fact that certain essential elements are proportionately very small it has been found impracticable to preserve a single scale 60 drawing and the true relative positions of the parts. For example, the brake-valve is represented as enlarged and the sectionized portion turned toward the observer to exhibit the valve-seat in full with the port added by 70 me in its proper place. Further increase in the scale is adopted for the second figure, with the intention of setting out plainly the contour and situation preferred for the new cavities in the rotary-valve face. Figs. 3, 4, 5, 6, 75 7, and 8 are explanatory diagrams indicating the valve-cavities and seat-ports in their various conjunctions corresponding to the different stations of the valve-lever.

I have illustrated and described my invention as forming part of the Westinghouse air-brake system, but do not limit myself to any particular apparatus.

Upon the drawings in Fig. 1 numeral 1 marks the engine brake-cylinder, connected by 85 pipe 2, including a pressure-reducing valve 3, with the triple valve 4. From the triple valve pipe 5 leads to train-pipe 6 and pipe 7 to auxiliary reservoir 8. All the parts so numbered are of the customary construction and operation, 90 the reducing-valve 3 being of the general character of that denominated a "regulating-valve" and shown in detail in Fig. 2 and fully described in United States Patent No. 557,463, dated March 31, 1896, granted to G. Westinghouse, Jr. Train-pipe 6 joins the engineer's 95 brake-valve 9, which has a circular valve-seat 10, possessing the port 11, extended by groove 12, the port 11, leading to atmosphere, port 13, leading to the train-pipe, cavity 14, and the remaining smaller ports required to carry out 100 the regular operations of the air-brake system. In addition to the usual ports I have provided a new opening 15 between port 11 and cavity

14, leading through the casing of the brake-valve and connected by pipe 16 with exhaust-port 17 of the triple valve.

Fig. 2 shows the face 18 of the rotary valve 5 having the customary large cavity 19 and adjacent thereto the relatively smaller port 20, also the groove 21 near the periphery and other ports or passages required to carry out the regular operations of the air-brake system. In addition to the usual cavities I have provided two new ones between port 20 and groove 21, number 22 designating the larger and 23 the smaller cavity. Both are of a similar oblong shape with parallel sides and rounded ends, and median lines drawn joining the ends of each interiorly would form portions of the same circumference described from the center of the valve-face. While the preferred form of the new cavities is shown 20 in the drawings, I do not limit myself solely thereto, and it is believed to be within the scope of my invention to change the location of these cavities, if desired.

Considering explanatory diagram Fig. 3, it 25 will be seen that at "full release" cavity 22 joins new port 15 with port 11, enabling the triple valve to exhaust the brake-cylinder through the engineer's valve instead of directly to air.

30 Fig. 4 shows the "new" or "engine-service" position fixed, usually, next in order from the release position. Air from the main reservoir is now admitted, by way of port 20 in rotary valve, cavity 14 in its seat, cavity 22 in valve, and new port 15 in seat, triple valve, and reducing-valve, to brake-cylinder on the locomotive, into which it is delivered at a pressure depending upon the adjustment of the reducing-valve 3, and the engine-brakes only are 35 set. New cavity 22 is intentionally restricted 40 in size in order that the brakes may be operated without undue rapidity or shock in bringing a slowly-moving engine or train to a standstill with the least possible expenditure of 45 air. Should it be expedient to hold the brakes on, the needed pressure will be maintained beyond ordinary leakage by the familiar action of the reducing-valve.

50 Fig. 5 indicates the "running position" of the parts, the charge in the brake-cylinder

passing to atmosphere by way of new port 15, cavity 23, and port 11, all of the engineer's valve. It is to be noted that the valve-lever may be quickly moved from "release" to "running" position without materially affecting the engine-brakes.

Figs. 6, 7, and 8 point out the positions of the cavities and ports "on lap" and in making the regular service application and "emergency application" of the entire brake system. No meeting between the new port and cavities takes place in either of these positions and no interference with the regular operation of the system occurs, the engine-brakes acting with the train-brakes in the ordinary manner and the changes in operation relating only to the release of the former, as stated.

Having thus described my invention, what I claim is—

1. In a locomotive air-brake, the combination with a brake-cylinder, triple valve and auxiliary reservoir, of an engineer's valve suitably connected with said devices and provided with an additional port in its seat opening through the casing of said valve, a pipe connecting said opening with the exhaust-port of the triple valve, the rotary or valve portion of said engineer's valve having additional cavities 22 and 23, substantially as described.

2. In a locomotive air-brake, the combination with a brake-cylinder, triple valve and auxiliary reservoir, of an engineer's valve suitably connected with said devices and provided with an additional port in its seat opening through the casing of said valve, a pipe connecting said opening with the exhaust-port of the triple valve, the rotary or valve portion of said engineer's valve having additional cavities 22 and 23, and a pressure-reducing valve introduced between said triple valve and brake-cylinder, substantially as described.

3. In testimony whereof I affix my signature in presence of two witnesses.

WILLIAM PARKS ALTER.
